UNITED STATES PATENT OFFICE.

ADOLPH C. RECKER, OF OAKVILLE, CONNECTICUT, ASSIGNOR TO THE CHASE COMPANIES, INC., OF WATERBURY, CONNECTICUT, A CORPORATION.

SHADE-SUPPORT FOR INCANDESCENT-ELECTRIC-LAMP SOCKETS.

1,383,662.

Specification of Letters Patent.

Patented July 5, 1921.

Application filed June 26, 1920. Serial No. 391,895.

To all whom it may concern:

Be it known that I, ADOLPH C. RECKER, a citizen of the United States, residing at Oakville, in the county of Litchfield and State of Connecticut, have invented a new and useful Improvement in Shade-Supports for Incandescent - Electric - Lamp Sockets; and I do hereby declare the following, when taken in connection with the accompanying drawings and the characters of reference marked thereon, to be a full, clear, and exact description of the same, and which said drawings constitute part of this application, and represent, in—

15 Figure 1, a broken view partly in elevation and partly in section of a shade-support embodying my invention, shown as in use;

20 Fig. 2, a broken view thereof in transverse section on the line 2—2 of Fig. 1, and looking downward;

Fig. 3, a view of the shade-support in elevation, its mounting-shell having been removed;

25 Fig. 4, a detached view in side elevation of the mounting-shell;

Fig. 5, a corresponding view of the binding-knob thereof;

Fig. 6, a detached plan view of the spider 30 employed to mount the binding-knob screw and to unite the ends of the bowed frame-arms at the shade-end of the support;

Fig. 7, a detached view in elevation of the cross-piece of the support.

35 My invention relates to an improvement in shade-supports of the type in which the shade-mounting means and the lamp-mounting means are rigidly connected by two, bowed wire frame-arms. Heretofore, the 40 lamp-ends of these arms have been fastened to lamp-mounting means in the form of a clamping-ring adapted to be spread open to receive a standard lamp-socket and provided with a set screw by means of which 45 the ring has been clamped thereupon, while the opposite or shade-ends of the arms have been fastened to shade-mounting means of various forms. The object of my present 50 invention is to simplify and improve the convenience and appearance of shade-supports of the type described.

With these ends in view, my invention consists in a shade-support comprising two, bowed wire frame-arms, shade-mounting 55 means secured to the said arms at the shade-

ends thereof, and lamp-mounting means fastened to the lamp-ends of the said arms and consisting of a threaded socket-receiving sleeve into which the lamp-socket may be introduced and which is threaded for co-action with the threaded lamp-receiving end thereof.

In carrying out my invention, as herein shown, the two bowed frame-arms 3, 3 of my improved fixture have their lamp-ends, 60 so to speak, straightened, flattened, and perforated for being secured by rivets 4 to a lamp-receiving ring 5 having its outer end formed with a bead 6 and its inner end threaded, as at 7, the said ring 5 being 65 adapted to receive the threaded lamp-receiving end 8 of a standard incandescent electric-lamp socket 9, the threads of the said ring and socket corresponding in pitch, and the socket being formed with an abutment shoulder 10, though this latter may be omitted, in which case the bead 6 of the ring 5 would abut against the annular shoulder 11 between the two ends of the lamp-socket.

80 The shade-mounting means applied to the opposite or shade-ends of the two frame-arms 3, may assume a variety of forms. As shown, the shade-mounting means consists of a mounting-shell 12 secured in place by a 85 removable, internally threaded binding-knob 13 applied to a screw 14, the headed inner end of which is mounted in a sheet-metal spider or union 15 having four, transversely arranged arms, of which the arms 16, 16 are 90 clasped over the inwardly bent shade-ends of the arms 3, while the arms 17, 17 are clasped over the inner portion of a shade-supporting cross-piece 18 arranged at a right angle to the ends of the arms 3, whereby I 95 form a four-point bearing, as it were, for the shade which is held against the four points of this bearing by means of the mounting-shell 12, which in turn is held in place by the binding-knob 13 on the screw 100 14. But, as explained, I do not limit myself to employing such shade-mounting means in conjunction with my improved lamp-mounting means. It will be noted that the lamp-receiving ring 5 is a one-piece ring 105 and provided with continuous threads and is thus adapted to be directly applied to the threaded lamp-receiving end 8 of a standard incandescent electric lamp-socket. No additional clamping means of any description 110

are required to adapt the fixture to be used in an inverted position, as shown, or in an upright position, in which the shade is reversed. In the inverted position, as for 5 indirect lighting, the entire weight of the shade and the parts forming the shade-support fall upon the lamp-receiving ring 5, which, on account of being screwed directly upon the socket, is amply strong for sus- 10 taining the weight and will not work loose.

I claim:

In a shade-support for threaded incandescent-lamp sockets, the combination with 15 two bowed frame-arms, shade-mounting means fastened to the shade-ends of the said arms, and lamp-socket mounting-means permanently fastened to the lamp-ends of the

said arms and consisting of a one-piece lamp-socket receiving-ring fastened to the lamp-ends of the said arms, and formed at its 20 inner end with threads for direct coaction with the threads at the lamp-receiving end of the lamp-socket, whereby, by the use of the said single ring, the said support and lamp-socket may be solidly screwed together 25 for the use of the said support, either in the upright or in the inverted position.

In testimony whereof I have signed this specification in the presence of two sub-scribing witnesses.

ADOLPH C. RECKER.
